(57) **CLAIM**

The ornamental design for an intervertebral implant, as shown and described.

DESCRIPTION

FIG. 1 is a perspective view of the intervertebral implant of the present invention showing the top, rear and left side; FIG. 2 is a perspective view of the intervertebral implant showing the bottom, front and right side; FIG. 3 is a top view of the intervertebral implant; FIG. 4 is a bottom view of the intervertebral implant; FIG. 5 is a left side view of the intervertebral implant; FIG. 6 is a right side view of the intervertebral implant; FIG. 7 is a rear view of the intervertebral implant; and, FIG. 8 is a front view of the intervertebral implant. Those portions shown in broken lines are for illustrative purposes only and form no part of the claimed design.
